UNITED STATES PATENT OFFICE.

GEORG ULLRICH, OF MAGDEBURG, GERMANY, ASSIGNOR TO FRIED. KRUPP AKTIEN-GESELLSCHAFT, GRUSONWERK, OF MAGDEBURG-BUCKAU, GERMANY, A JOINT-STOCK COMPANY.

MAGNETIC SEPARATOR.

1,129,822.

Specification of Letters Patent. Patented Feb. 23, 1915.

Application filed July 3, 1913, Serial No. 777,217. Renewed January 21, 1915. Serial No. 3,631.

To all whom it may concern:

Be it known that I, GEORG ULLRICH, a subject of the King of Bavaria, and resident of Magdeburg, German Empire, have 5 invented certain and useful Improvements Relating to Magnetic Separators, of which the following is a specification.

This invention relates to magnetic separators and has particular reference to separators of the kind in which the material to be treated is made to travel in a longitudinal direction between the surface of a magnet pole and a horizontally rotatable cylinder serving as armature thereto, the said 10 cylinder being composed of annular or disk-shaped bodies which are axially adjustable upon the cylinder shaft and are preferably tapered at their peripheries. In this form of apparatus the strength of the magnetic field extending across each disk or group 15 of disks between upper and lower poles has been rendered capable of regulation by using interchangeable or adjustable magnet pole pieces beneath the cylinder. It would 20 be much more advantageous to be able to effect the regulation of the magnetic field strength from above, but hitherto such regulation has necessitated a changing of the disks or of equivalent ring-shaped members, which is inconvenient.

The chief object of the present invention is to provide a magnetic separator of the horizontal rotating cylinder type in which the adjustment of the magnetic field 25 strength at different parts can be readily effected without involving any changing of parts of the separator.

According to the present invention the magnetic separator comprises a horizontally 30 rotatable cylinder composed of annular or disk-shaped bodies, and a lower pole having a longitudinally inclined surface or upper face, the said pole and the disks being adapted for longitudinal adjustment relatively to one another. Consequently with 35 any, even the slightest, displacement of any one of the disks, the distance separating its sharp edge from the surface of the lower pole is altered, with the result that the 40 strength of the corresponding zone is modified also.

One embodiment of the invention is illustrated by way of example in the accompanying drawing, in which:

55 Figure 1 is a longitudinal section through a cylinder separator constructed in accord-

ance with the invention, and Fig. 2 is a cross section on the line A—B of Fig. 1. Figs. 3 and 4, show, in longitudinal section, two modifications of Fig. 1.

The separator illustrated is one with two magnetic fields, one field extending between the cylinder and an upper pole, and the other between the said cylinder and a lower pole. It will of course be understood that 60 the invention can also be applied to separators with only one magnetic field and also to those with more than two such fields.

a is the upper pole and *b* the lower pole of each magnetic field; between these poles 70 the cylinder rotates; this cylinder is composed of annular or disk-shaped bodies *c* displaceably secured to a hub *e* mounted on the shaft *d*. In the example illustrated in Fig. 1, the disks *c* are internally threaded, 75 and the hub *e* is externally threaded, but adjustability can be provided for in other ways. The surface or upper face of the lower pole *b* is common to the disks and lies obliquely to the axis of the cylinder. It 80 is not necessary that it should present a plane surface as in the example illustrated in Fig. 1. It might be stepped, or divided or both stepped and divided into lamellæ *b*³, Fig. 3, transverse with respect to the 85 axis of the cylinder, in order to permit of modifying the inclination of the surface of the pole as desired, and also to permit of effecting adjustment of the magnetic zones from below by means of set screws *j* if desired, instead of at the cylinder, for example for fine adjustment during operation. The upper pole may also be divided into lamellæ *a*³, having individual set screws *k* to permit of regulating the pull exerted by the lower 90 pole upon the intervening cylinder. In some cases it might be preferable to construct the lower pole as a solid block *b*⁴ which is displaceable longitudinally, parallel to the axis of the shaft *d*, by means of a 95 set screw *l*, see Fig. 4.

An inclined table *f* is arranged above each half of the lower pole *b* and the material to be separated is delivered to these tables at *g*. The magnetic material is attracted into 100 the several annular magnetic zones onto the sharp edges of the disk *c*, and by the rotation of the cylinder it is conducted by the disks out of the magnetic field. The material then falls from the disks or is removed mechanically. The non-magnetic material slides down the tables into a chute 110

h, which in the example illustrated is common to both halves of the magnetic field.

If it be desired to modify the magnetic strength of the zones formed between the 5 several disks *c* and the pole *b*, the disks in question are shifted. For example, if one of the disks of the left hand magnetic field be screwed to the left, its sharp edge approaches the surface of the lower pole and 10 the zone is strengthened, whereas by screwing to the right the zone in question is weakened. In other respects the construction of the separator can be modified as desired provided that the result is attained that by 15 relative axial displacement between the lower pole and the cylinder disks, either individually or collectively, and a modification of the strength of field in the several magnetic zones is brought about. For example instead of adjusting the disks on the 20 cylinder, the inclined surface *d* of the lower pole might well be displaced, and the cylinder be stationary, or both might be displaced.

25 Having now particularly described and ascertained the nature of my said invention and in what manner the same is to be performed, I declare that what I claim is:—

1. A magnetic separator having a horizontal rotatable cylinder, an underlying magnet pole, disks serving as armature to said underlying magnet pole, means for feeding the material between the cylinder and the pole face, the magnet pole being

30 formed with a longitudinally inclined surface or upper face, means for longitudinal adjustment of the pole and the disks, relatively to one another, substantially as and for the purposes specified.

40 2. A magnetic separator comprising a longitudinally extending horizontal shaft carrying disks thereon axially adjustable individually and collectively and tapered at their peripheries, an underlying magnet pole having a longitudinally inclined surface or upper face, and means whereby the material to be separated is conducted longitudinally between the magnet pole and the disks, substantially as and for the purpose 45 specified.

50 3. A magnetic separator having a horizontal rotatable cylinder, an underlying magnet pole, disks with graded diameters serving as armature to said underlying magnet pole, means for feeding the material between the cylinder and the pole face, the magnet pole being composed of transversely arranged lamellæ oppositely graded to said disks and capable of individual adjustment 55 relatively to the periphery of the cylinder disk.

4. A magnetic separator having a horizontal rotatable cylinder, an underlying magnet pole, disks serving as armature to said pole, means for feeding the material between the 60 cylinder and the pole face, said magnet pole having inclined surfaces in the axial direction of the cylinder, means for adjusting the pole perpendicularly relative to the axes of the disks.

70 5. A magnetic separator having a horizontal rotatable cylinder, an underlying magnet pole, disks serving as armature to said pole, means for feeding the material between the cylinder and the pole face, said magnet pole 75 having graded inclined surfaces in the axial direction of the cylinder, means for adjusting the pole perpendicularly relative to the axes of the disks.

6. A magnetic separator having a horizontal rotatable cylinder, an upper and a lower pole, disks serving as armature to said poles, means for feeding the material between the cylinder and the lower pole face in the direction of the axes of the disks, 85 said poles being composed of lamellæ arranged transversely as regards the line of feed through the field and capable of rectilinear, individual adjustment relative to said cylinder disks.

90 7. A magnetic separator having a horizontal rotatable cylinder, an upper and a lower pole, disks serving as armature to said poles, means for feeding the material between the cylinder and the lower pole face in the direction of the axes of the disks, said poles 95 being composed of lamellæ arranged transversely as regards the line of feed through the field and capable of rectilinear, individual adjustment relative to said cylinder 100 disks, each of said lamellæ having inclined surfaces facing said cylinder!

8. A magnetic separator having a horizontal rotatable cylinder; an upper and a lower pole, disks serving as armature to said poles, 105 means for feeding the material between the cylinder and the lower pole face, said disks being of different diameters and arranged so that their peripheries coincide with the outer surfaces of a cone and the surfaces 110 of said poles forming inclined steps approximately following the inclination of said cone, the direction of the feed of material taking place in the direction of the axis of the cylinder.

115 The foregoing specification signed at Magdeburg, this 14th day of June, 1913.

GEORG ULLRICH.
